Primary Examiner — Sharon S Oum(74) *Attorney, Agent, or Firm* — McGarry Bair PC; Mark A. Davis(57) **CLAIM**

The ornamental design for a ceiling fan light kit as shown and described.

DESCRIPTION

FIG. 1 is a bottom perspective view of a ceiling fan light kit, shown in the environment of a ceiling fan, showing my new design;

FIG. 2 is a top perspective view thereof, having the ceiling fan environment removed;

FIG. 3 is a top view thereof;

FIG. 4 is a bottom view thereof;

FIG. 5 is a front view thereof; and,

FIG. 6 is a side view thereof.

Portions of the ceiling fan, ceiling fan light kit, and ceiling fan environment are shown in broken lines. Portions shown in broken lines form no part of the claimed design.

1 Claim, 6 Drawing Sheets(56)
